UNITED STATES PATENT OFFICE

WILLIAM F. OBERHUBER, OF LANSDOWNE, PENNSYLVANIA

SWITCH LATCH

Application filed November 5, 1925. Serial No. 66,953.

My invention relates to latches or locks for holding electric switch knives in closed position against the electromagnetic opening stresses incidental to short circuiting or other 5 abnormally large flow of current through the switch.

A purpose of my invention is to lock a switch knife to a post by wedge action.

A further purpose is to provide a switch 10 knife with a wedging roller latch.

A further purpose is to latch a switch knife shut by wedging a roller between the head of a stationary post and the sloping wall of a housing, and to have a switch opening member 15 lift the roller from wedging position as it moves to open the switch.

A further purpose is to fasten a housing to the outer end of a double throw knife, aperturing the housing upon opposite sides 20 to receive locking posts, one at the side of each throw, to taper the inside walls of the housing toward each aperture, to resiliently press roller carriers apart, within the housing and to lift one of the carrier members 25 preliminarily to opening the knife.

A further purpose is to wedge the rollers of a switch lock forwardly and inwardly for locking purposes and to lift the rollers preliminarily to opening the switch.

30 A further purpose is to lock a switch by lateral gripping engagement of clamp members inwardly pressed by sloping side walls and to lift and spread the clamp members as a preliminary to opening the switch.

35 Further purposes will appear in the specification and in the claims.

I have elected to show three forms only of my invention, selecting forms, however, that 40 well illustrate the principles involved and which are efficient in operation and inexpensive in manufacture.

Figure 1 is a side elevation illustrating one form of my invention applied to a double 45 throw switch.

Figure 2 is a top plan view of Figure 1.

Figure 3 is a section to enlarged scale taken on line 3—3 of Figure 1 showing the latch in latching position.

Figure 4 is a view similar to that of Fig-

ure 3 but with the latch mechanism in position of release.

Figure 5 is a section of Figure 3 taken upon the line 5—5.

Figure 6 shows a side elevation of a single 55 throw switch having applied to it a somewhat different form of my invention.

Figure 7 is a top plan view of Figure 6.

Figure 8 is a section to an enlarged scale 60 taken upon line 8—8 of Figure 7.

Figure 9 is a view corresponding to Figure 8 but showing the latch mechanism in different position.

Figure 10 is a section of Figure 8 taken 65 upon the line 10—10.

Figure 11 is a side elevation showing a double throw switch having applied to it a different form of my invention.

Figure 12 is a top plan view of Figure 11.

Figure 13 is a section to enlarged scale 70 taken upon line 13—13 of Figure 12 showing the latch mechanism in closed position.

Figure 14 is a view corresponding to Figure 13 but with the latch mechanism raised into position of release.

Like numerals refer to like parts in all figures.

Describing in illustration and not in limitation and referring to the drawings:

In Figures 1 to 5 the switch knife 20 is 80 pivoted at 21 in the usual way upon a post 22 bolted to the base 23 and adapted to make contact alternatively with either one of the spring contacts 24 and 25.

At the outer end of the knife I mount a 85 housing member 26, apertured upon the opposite sides at 27 and 28 to receive the enlarged upper end 29 of a stationary post 30 when thrown in one direction and to receive the enlarged upper end 31 of the post 32 when thrown in the other direction.

The walls of the housing member taper 90 converging toward the apertures. Taking the position of the switch in Figures 1—5, at the left of Figures 1 and 2, rollers 33 and 34 within the carrier member 35 engage the tapering walls 36 and 37 of the housing and simultaneously engage opposite lower portions of the enlargement 29 of the post when the roller carrier member is in latching posi-

tion (Figure 3). Similar rollers 38 and 39 within a similar roller carrier 40 are provided upon the upper side of the housing for use when the switch is thrown to the right in 5 Figures 1 and 2, and the carrier members are provided with opposing lugs 41, 42 and 43, 44 and intermediate springs 45, 46 which placed upon diagonally opposite sides of the opposing carriers press these carriers outwardly into latching position. The housing member is fastened in any suitable way, as by welding, to the outer end of the switch 10 knife.

An opening member 47 is provided with a 15 shank 48 which extends into the housing axially of the knife and is loosely pivoted to the end of the knife at 49. The outer end of this opening member is shown as having a ring 50 as seen in Figure 1, to cooperate with the 20 usual operating hook upon the end of a pole. The hook engages in the ring to release the latch and open the switch.

The carrier members 35 and 40 are provided with hook lugs 51, 52 which respectively 25 hook across opposite sides of the shank 53 of the opening member. The arrangement is such that when the ring member is raised to open the switch, the shank 53 engages the carrier lug 51 and raises the carrier before 30 the ring member engages the housing to lift the knife of the switch.

Figures 6 to 10 show a somewhat different form of my invention applied to a single throw knife and in which the housing conveniently circular is shown as held to the 35 knife by screws.

The stationary post 54 is in this form shown with circular section to fit within the circular, upwardly flared opening 55 while in the 40 first form the section is rectangular.

The ball carrier 56 is bored at 57 to receive the enlarged end 58 of the post and is provided with a tapered or conical end 59 recessed at circumferentially spaced intervals 45 at 60 to receive the wedging rollers, here balls, 61.

Three of these balls are shown in the figure uniformly spaced around the bore of the carrier.

50 These recesses are made sufficiently large to permit the balls to engage the outside of the post but are too small to permit them to pass into the bore 57. This is necessary in order that they may not escape from the carrier when the knife is open.

The carrier is resiliently pressed axially into the conical aperture by means of a surrounding spring 62 compressed between a shoulder 63 on the upper end of the conical 60 portion of the carrier and a cover member 64 which is bored at 65 to receive and guide the upper end of the carrier.

The carrier has a limited freedom of motion axially and is provided with a shank 66 65 extending upwardly through the top of the

cover. A ring 67 is fastened to the shank 66 above the cover for use in releasing the lock and opening the switch.

Usually the switch is placed out of reach from the floor and is opened and closed by 70 means of a pole, a hook upon the end of the pole engaging the ring which with opening movement first releases the wedging balls by raising the carrier and then opens the switch.

When the switch is closed the balls latch 75 under the head 68 of the post and by wedging between the tapered surface of the housing and the lower portion of the head of the post prevent any sudden stresses from opening the knife.

80 Figures 11 to 14 show a third form of my invention applied to a double throw knife. The stationary posts 69 and 70 are ringed or threaded at their heads or upper ends and these ringed or threaded ends cooperate with 85 divided nuts 71 and 72 carried on opposite sides of a housing 73.

The housing is apertured as in the other forms to receive the stationary posts and the 90 walls of the housing are given a wedge taper at the apertures.

95 The divided nuts comprise portions 74 and 75 which in latching position are wedged together at the lower end by the tapered walls of the housing and pressed downward resiliently by a carrier 76.

100 By means of the carrier the individual portions of the nut are supported on the top at the sides at 77 away from the line of division. This support is a loose one and when the carrier is raised the nut portions spread at the bottom, the lower outside edges of the portions moving upwardly and outwardly along the diverging walls of the housing while the upper ends of the nut portions maintain contact at 78.

105 This is best seen in Figure 14 where the lower carrier is raised, spreading the divided nut portions, preparatory to opening the switch. The carrier 77 comprises telescoping 110 members 79 and 70. The lower member 79 is bored axially at 81 to receive a shank 82 fitting into the bore of the lower carrier.

115 These intersliding portions of the carriers are perforated to pass rod 83 of an opening member 84, loosely connected at 85 to the inner end of the housing.

120 The housing is suitably cut away at 86 to let the opening member extend outwardly and the outer end of this opening member is shown with the usual ring for pole operation of the switch.

125 A spiral spring 87 is compressed between the bottom of the bore 81 of the lower carrier and the lower end 88 of the upper carrier. This resiliently presses the telescoping carriers toward relative extension and normally maintains the divided nuts pressed into their respective apertures, maintaining them normally with the divided portions pressed 130

together by wedging against the converging walls of the housing, yet free to be moved upwardly against the action of the spring.

Normally the lower carrier is provided with a downwardly directed face 89 engaging an upwardly directed face 90 of the opening member, when that member is in mid-position, and correspondingly the upper member is provided with an upwardly directed face 91 engaging a downwardly directed face 92 of the opening member when that member is in mid-position.

When the ring 67 is pulled in an opening direction, the lower carrier is raised by reason of engagement between the faces 89 and 90 from the position shown in Figure 13 to that shown in Figure 14.

This releases locking engagement between the nut and the threaded or ringed post and leaves the knife free to open if the ring be moved further in an opening direction.

It will be seen that in all of the forms shown the housing fastened to the end of the knife and the stationary post are locked together by wedging the holding member between the head of the post and converging walls of the housing; that in all of the forms a carrier is provided which resiliently presses the wedging member toward locking position; that in all forms the opening member operates the carrier to move the wedging member from locking position before it operates to open the knife.

In two of the forms shown the locking by wedging engagement between the tapered walls of the housing and the end of the stationary post is one of roller wedging, the rollers simultaneously engaging the taper walls of the housing and a lower portion of an enlargement of the head of the post.

Obviously the roller may either be cylindrical or spherical and I show spherical rollers in one form and cylindrical rollers in another.

The carrier latches of double throw knives may be counterparts as shown in the first form or one telescoping within the other as shown in the second form.

In either event they are resiliently pressed apart to maintain the wedge (whether roller or divided nut), pressed resiliently to its position for locking with the post.

Where the carrier members are counterparts it is convenient to press them apart with a pair of springs which engage diagonally opposite counterpart lugs of the opposing carriers, while in the telescoping form a single spring is all that is needed.

When the knife is double throw the opening member preferably extends out axially of the knife so as to be adapted to open in precisely the same way in either direction, while in a single throw switch the opening member may be carried upon the upper extension

of the carrier member as illustrated in the second form.

Obviously in view of my invention and disclosure very considerable variations and modifications to meet individual whim or particular need will occur to others skilled in the art and it is my wish therefore to claim all such in so far as they fall within the reasonable spirit and scope of my invention.

Having thus described my invention, what I claim as new and desire to secure by Letters Patent is:—

1. A pivoted knife switch, a wedging roller latch having bodily movement with respect to the member by which it is carried and a cooperating member therefor, one carried by the outer part of the knife, and adapted to be tightened to prevent movement by electro-magnetic-stress-operated throw of the switch.

2. A pivoted switch knife, a wedging roller latch carried by the end of the knife adapted to hold the switch closed and tightened by electro-magnetic-stress-operated withdrawal movement of the knife, a cooperating member with which the roller latch engages to lock and a release therefor adapted to release the latch and subsequently to open the switch.

3. A double throw switch having a knife, a wedging roller latch and engaging member therefor, one of them carried by the knife and adapted to operate at each end of the throw and tightened by electro-magnetic-stress-operated withdrawal movement of the knife to retain the knife fixedly against movement and a release for the latch adapted to operate before opening movement of the knife.

4. In a switch latch, a pivoted switch knife, a fixed post, a switch latch carried by the knife and engaging the post and a wedge carried by the knife free to move bodily with respect to the knife and adapted to tighten the latch with electromagnetic-stress-operated opening movement of the knife.

5. In a switch latch, a pivoted switch knife, a fixed post, a switch latch carried by the knife and engaging the post, a wedge carried by the knife adapted to tighten the latch with electromagnetic-stress-operated opening movement of the knife, and switch opening mechanism releasing the latch preliminary to opening movement of the blade.

6. A switch knife, a housing fastened to the outer end thereof and apertured, a stationary post in registry with the aperture and received therein when the knife is closed, walls of the housing converging to the aperture, a clamp member latching the post to the housing by wedging between the taper walls and the post, a carrier adapted to position the clamping wedge and resiliently pressing the clamping wedge into latching position and a knife opener moving the carrier to release the wedge and subsequently opening the knife.

130

7. In a switch latch, a switch knife, a casing secured to the end of the knife, a post having an enlarged head, adapted to be surrounded by the casing in the closed position of the switch, rollers within the casing adapted to move beneath the enlarged head, means for pressing the rollers beneath the head, walls within the casing adapted to wedge the rollers against the post with opening movement of the switch, knife and switch-opening mechanism adapted to engage the rollers and draw them free from the head.
8. In a switch latch, a pivoted switch knife, a casing secured to the end of the knife, a post having an enlarged end, spring-pressed rollable means for engaging beneath the enlarged end, a wedged side wall within the casing adapted to press the rolling means against the post and release mechanism for the rollable means pulled to open the knife.
9. In a switch latch, a pivoted switch knife, a casing secured to the end of the knife, a pair of opposite parallel rollers within the casing, a fixed post adapted to be surrounded by the casing and enlarged at its end to provide recesses for the rollers, a carrier adapted to move the rollers into and out of latching position, a spring pressing the carrier to latching position, wedges within the casing adapted to tighten the rollers against the post with opening movement of the switch knife and an opening member connected with the carrier to move the carrier and subsequently open the switch knife.
10. A double-throw knife, a stationary post at each end thereof, a head upon each post, a housing fastened to the end of the knife and apertured on one side to receive one of the posts and on the other side to receive the other post, opposing walls of the housing tapering toward each aperture, a pair of roller-carriers spring-pressed apart toward the respective apertures, a pair of opposing rollers in each carrier adapted to lock the housing to the respective posts by wedging against the tapering walls and opposite sides of the respective heads, and a lock-release having a pivoted shank extending axially of the knife between the carriers and adapted to move either carrier into a position of latch release and then to open the switch when moved in an opening direction.

WILLIAM F. OBERHUBER.
